UNITED STATES PATENT OFFICE.

MARVIN SMITHEY, OF LAWRENCEVILLE, VIRGINIA.

METER.

1,252,622.

Specification of Letters Patent. Patented Jan. 8, 1918.

Application filed August 14, 1916. Serial No. 114,877.

To all whom it may concern:

Be it known that I, MARVIN SMITHEY, a citizen of the United States, and a resident of Lawrenceville, in the county of Brunswick and State of Virginia, have invented 5 certain new and useful Improvements in Meters; and they consist in the combinations, constructions, and arrangements hereinafter described and claimed.

An object of the invention is to provide 10 a simple form of meter, in which a speedometer is combined with a number of odometers, each odometer being adapted to register the mileage of a particular portion of 15 the vehicle, such as a particular tire.

A further object of my invention is to 20 provide a device of the type mentioned, which has few parts and which is cheap to manufacture, and which will not easily get out of order.

A further object of my invention is to 25 provide a device comprising a plurality of odometers with a single means for driving the odometers in succession.

Other objects and advantages will appear 30 in the following specification and the novel features of the invention will be particularly pointed out in the appended claims.

My invention is illustrated in the accompanying drawings, forming a part of this 35 specification, in which;

Figure 1 is a perspective view showing the device in position on a car;

Fig. 2 is a face view of the device, showing 40 certain parts in section;

Fig. 3 is a diagrammatic view showing the development of the drum which bears 45 the odometers;

Fig. 4 is a section along the line 4—4 of 50 Fig. 2;

Fig. 5 is a section along the line 5—5 of 55 Fig. 4;

Fig. 6 is a section through the end of one of the odometer shafts showing the shiftable 60 star wheels; and

Fig. 7 is a perspective view of a means for shifting any of the star wheels.

In carrying out my invention, I provide a 65 casing 1 which is preferably circular as shown in the drawings. The cover for this casing consists of a ring 2 carrying a plate of glass 3. The ring is rotatable on the casing, being held in position by means of cleats or similar guide members 4.

The casing 1 is provided with an extension

1^x which forms a housing for a pair of bevel gears 5 and 6, respectively, the former being on the end of the stub shaft 7 by means of which the meter may be connected with a movable part of the vehicle such as the wheel, 60 the stub shaft also bearing a worm 8 arranged to engage a worm wheel 9 disposed within the housing at the end of the shaft 10.

As will be seen from Fig. 4, the shaft 10 is provided with a worm 11 at its opposite 65 end which engages a worm wheel 12 on a shaft 13 bearing a worm 14 in engagement with the worm wheel 15 on a shaft 16. The shaft 16 bears a gear 17 arranged to engage an internal gear 18 on the interior of a rev- 70 oluble sleeve 19, one end of which is journaled in a partition 20, the other end fitting over an inwardly projecting sleeve 21 so as to rotate thereon, the sleeve 21 being secured to the casing 1.

The partition 20 is part of a drum 22 and has a portion 22^x provided with an extension having a gear ring 22^y, the latter being in engagement with a gear ring 23 carried by the annular plate 24 secured to the ring 2. 80 The opposite end 26 of the drum is rotatably supported on rollers 27, see Fig. 5, carried by the partition 28.

Disposed between the partition 20 and the end of the drum 22^x is a series of odometers, 85 while another series is disposed between the partition 20 and the end 26. These odometers are arranged in staggered relation and the ends of the odometer shafts all project through the end of the drum 22^x. I have 90 indicated the odometers in general by the numeral 30.

Mounted on the shaft of each odometer is a star wheel 31, whose hub is provided with a spring which enters a slide-way 31^x in the 95 shaft 32, notches 32^y and 32^z being provided into which a portion of the spring may enter thereby holding the wheel in position.

Keyed to one end of the sleeve 19 is a collar 34 which is provided with a lug or outwardly extending finger 35 disposed in the path of the star wheel when the latter is out of position, i. e. that shown in Fig. 6. The end of each of the odometer shafts 32 is provided with a clutch member 32^c arranged to engage a corresponding clutch member 36^c, on the end of a shaft 36 which is held normally in its outer portion by means of a spring 37. Each of the star wheels 31 is adapted to be shifted by means of a device, 110

shown in Fig. 7. In this figure, it will be seen that I have provided a slidable shaft 40 having a handle 41 at one end and a pair of laterally extending engaging plates 42 at the opposite end, these plates being spaced apart and being held in spaced relation by means of a bridge 43 so that the plates may be brought into position to engage a star wheel between them, while at the same time 10 being constructed so as to permit the normal revolution of the drum carrying the star wheels without engagement of the star wheels with the plate.

Referring now to Figs. 4 and 6, it will be 15 seen that the bevel gear 6 is on the end of the shaft 25 which extends through the partition 28, the end of the shaft being provided with a split ring magnet 46 arranged to operate on a wheel 47 having a hub 48 upon 20 which the magnet exerts a magnetic drag when the device is in operation. The wheel 47 is mounted on a bracket 49 secured to a casing 1 of the device.

From the foregoing description of the 25 various parts, the operation thereof will be readily understood. The instrument is attached in the ordinary manner to a flexible transmission. The rotation of the shaft 45 causes the operation of the speedometer in 30 a well known manner. Rotation of the shaft 10 causes rotation of the sleeve 19, through the medium of members 11 to 18, inclusive. This carries around with it the lug 35 on the collar 34 and this lug engaging the star 35 wheels in succession, turns them and thus operates the odometers. These odometers as has been said before pertain to particular features of the vehicle, such as particular tires. If it is desired to bring any odometer 40 into reading position, that is to say before the opening 50 in the top plate 51, then the ring 2 is grasped and turned. The drum bearing the odometers will be turned through the engagement of the gears 23 and 25 so 45 as to bring the desired odometer into reading position. By pushing inwardly on the thumb wheel 52 on the end of the shaft 36, the cup members 32^c and 36^c are brought together so as to permit the resetting of the 50 odometer. If now it is desired to put any odometer out of operative relation with the rest of the mechanism then the handle 41 is manipulated so as to bring the plates 42 and 43 on opposite sides of the particular 55 star wheel, when by pushing inwardly the wheel may be moved from the position shown in Fig. 6 to that shown in dotted lines in Fig. 4, the spring entering the notch 32^s, see Fig. 6, so as to retain the star wheel in a 60 fixed position, in which position it will not be engaged by the actuating lug 35. It is only necessary to reverse this process by pulling the star wheel forward into its normal position in order to put it into operation 65 in connection with the rest of the ma-

chine. The device requires comparatively little power because the star wheels are engaged in succession, and although I have shown eight odometers, yet no more power is required to drive the eight than to drive one. The device is very compact and being made of relative few parts is not liable to easily get out of order. 70

The term toothed wheel as used in the claims is designed to include any wheel, such as a gear, a Geneva movement, or any other wheel which has one or more teeth by means of which it may be positively actuated. 75

I claim:

1. In a meter, a casing, a plurality of 80 odometers, rotatably mounted within the casing, each odometer being provided with a toothed wheel for operating the same, each toothed wheel being movable with respect to the shaft of its individual odometer, means disposed within the casing for engaging the said wheels in succession to operate them, and means for moving any one of said wheels at will to bring it out of engagement with said operating means. 85

2. In a meter, a casing, a drum rotatably disposed within the casing, a plurality of 90 odometers carried by said drum, each of said odometers being provided with an individual shaft, a toothed wheel slidably mounted on the shaft of each of said odometers, a rotatable actuating member disposed within the casing and arranged to engage the said 95 wheels in succession when the latter are in their normal position on their odometer shafts, means for rotating the drum for bringing any odometer into the desired position, and oscillatable means for forcing any of the toothed wheels out of its normal position and out of the path of engagement with 100 said actuating shaft. 105

3. In a meter, a casing, a drum rotatably disposed within the casing, a plurality of 110 odometers carried by said drum, each of said odometers being provided with an individual shaft, a toothed wheel slidably mounted on the shaft of each of said odometers, a rotatable actuating member disposed within the casing and arranged to engage the said 115 wheels in succession when the latter are in their normal position on their odometer shafts, means for rotating the drum for bringing any odometer into the desired position, slidable means for forcing any of the toothed wheels out of its normal position 120 and out of the path of engagement with said actuating shaft, said means comprising a slidable rod and a pair of plates carried by the rod and spaced apart to receive the toothed wheel, and means for frictionally 125 retaining the toothed wheel in the operative or inoperative position.

4. In a meter, a casing provided with a laterally extending sleeve, a second sleeve 130 rotatably mounted at one end on said first

named sleeve, means for rotatably supporting the opposite end of said second named sleeve, a drum rotatably mounted within the casing, a plurality of odometers, each odometer being provided with a star wheel, means carried by said second named sleeve for engaging the star wheels in succession, and means for rotating said second named sleeve.

5. In a meter, a casing provided with a laterally extending sleeve, a second sleeve rotatably mounted at one end on said first named sleeve, means for rotatably supporting the opposite end of the second named sleeve, a drum rotatably mounted within the casing, a plurality of odometers, each odometer being provided with a star wheel, means carried by said second named sleeve for engaging the star wheels in succession, means for rotating said second named sleeve, each of said star wheels being movable on its odometer shaft, and means for moving

any star wheel into or out of operative position with the actuating mechanism.

6. In a meter, a casing provided with a laterally extending sleeve, a second sleeve rotatably mounted at one end on said first named sleeve, means for rotatably supporting the opposite end of said second named sleeve, a drum rotatably mounted within the casing, a plurality of odometers, each of said odometers being provided with a star wheel, means carried by said second named sleeve for engaging the star wheels in succession, means for rotating said second named sleeve, each of said star wheels being movable on its odometer shaft, means for moving any star wheel into or out of operative position with the actuating mechanism, and means for retaining the star wheels in their operative or inoperative position.

MARVIN SMITHEY.
